INVENTOR.

ORA D. McCLINTOCK

BY

Bradley L. Benson

ATTORNEY

UNITED STATES PATENT OFFICE.

ORA D. MCCLINTOCK, OF SAN FRANCISCO, CALIFORNIA.

HAIR CURLER.

Application filed October 10, 1921. Serial No. 506,541.

To all whom it may concern:

Be it known that I, ORA D. MCCLINTOCK, a citizen of the United States of America, residing at 450 Ellis Street, San Francisco, 5 in the county of San Francisco and State of California, have invented certain new and useful Improvements in Hair Curlers, of which the following is a specification.

The present invention is an improved 10 hair curler and is an improvement over my United States Patent No. 1,373,968, issued on April 5, 1921.

The object of this invention is to simplify and improve the operation and manufacture 15 of my hair curler. Another object is to provide a curler which may be worn overnight without inconvenience or discomfort by the wearer, and which is entirely rubber covered to prevent slipping of the hair or in- 20 jury thereto.

In the accompanying one sheet of drawings, Fig. 1 is a side elevation partly in section of my improved curler.

Fig. 2 is a side elevation of one member of 25 my curler, showing the method of engaging therein a strand of hair.

Fig. 3 is a view similar to Fig. 2, but showing the strand of hair curled about the curler and the engaging member bent to se- 30 cure the end of the strand.

Fig. 4 is a view illustrating the use of my device in forming what is termed a wave, instead of a curl.

Referring to the drawings, the numeral 35 1 indicates a medial loop or eye in a member of substantially a hair-pin shape. This member is formed of soft wire indicated at 2, Fig. 1, which is surrounded by a covering of rubber as shown at 3.

40 The purpose of the loop or eye 1 is to engage a strand 4 of human hair, as shown in Fig. 3, the hair being inserted through the pin members as shown in Fig. 2.

After the strand 4 is in the eye 1, a piece 45 of rubber tubing 5 is slid over the hair-pin member until it encounters the eye 1. The strand is then wrapped around the tube 5 as indicated at 6. In this operation curls are formed, such as are worn by girls. In

wrapping the strand of hair, the strand is 50 flattened and overlapped at each turn around the tube 5. This forms a continuous spiral curl with a solid wall when the curler is removed. The ends 7 of the hair-pin member are now bent upwardly to engage the end of the coil to prevent unwinding. The hair, which has preferably been previously moistened, dries out and leaves a lasting coil, such as is commonly worn by 55 young ladies.

Older persons use my curler as shown in Fig. 4, in which the strand 4 is not admitted between the ends of the hair-pin member but is coiled, as at 8, around the tube 5 and held at both ends by returning the eye 1 and 60 the ends 7 at the ends of the tube 5.

In this operation the strands 4, instead of being flattened and overlapped as before, is twisted by the coiling operation in such a manner that the coil is in the form of a 70 helix which in turn is wrapped helically around the tube 5.

This results when the curler is removed in an undulating strand of a wavy appearance which does not resemble a curl.

In reducing my invention to practice and marketing it, I have found that I can dispense with tape and loops in the end of the hair-pin member, and that the device is better adapted to use on the hair by making 80 the hair-pin member of one strand and having it rubber covered.

I claim:

1. A hair curler comprising a rubber covered hair-pin member of soft wire provided 85 with a medial loop, and a piece of rubber tubing adapted to surround the ends of said hair-pin member and be engaged thereon by returning the ends of said hair-pin member.

2. A hair curler comprising a rubber tube, and a flexible hair-pin member formed of soft wire and provided with a rubber covering, the said hair-pin member provided with a loop at one end larger than the diameter 95 of said tube.

In testimony whereof I affix my signature.

ORA D. MCCLINTOCK.
